UNITED STATES PATENT OFFICE.

PARNAG A. ADAMIAN AND ANTON DAHAN, OF BOSTON, MASSACHUSETTS.

DESIGN FOR A CASING FOR CIGAR-LIGHTERS.

44,080.

Specification for Design.

Patented May 27, 1913.

Application filed November 25, 1912. Serial No. 733,539. Term of patent 14 years.

To all whom it may concern:

Be it known that we, PARNAG ADAM ADAMIAN and ANTON DAHAN, citizens of the United States, residing at Boston, in the county of Suffolk and State of Massachusetts, have invented a new, original, and ornamental Design for a Casing for Cigar-Lighters, of which the following is a specification, reference being had to the accompanying drawing, forming part thereof.

Figure 1 is a side elevation of the cigar lighter, and Fig. 2 is a top plan view thereof.

We claim—

The ornamental design for a casing for cigar lighters, as shown.

P. A. ADAMIAN.
A. DAHAN.
